UNITED STATES PATENT OFFICE.

THEODORE PETERS, OF FERDINAND, INDIANA, ASSIGNOR TO THE PET-SON PUMP COMPANY, OF FERDINAND, INDIANA, A CORPORATION OF INDIANA.

DOUBLE-ACTING WELL-PUMP.

1,302,210.

Specification of Letters Patent. Patented Apr. 29, 1919.

Application filed May 26, 1917. Serial No. 171,312.

To all whom it may concern:

Be it known that I, THEODORE PETERS, a citizen of the United States, residing at Ferdinand, Indiana, have invented a certain new and useful Improvement in Double-Acting Well-Pumps, of which the following is a full, clear, and exact description, such as will enable others skilled in the art to which it appertains to make and use the same.

This invention relates to pumps of the kind that are used for drawing water from wells.

The main object of my invention is to provide an efficient double acting pump of simple design that can be manufactured at a low cost.

Another object is to provide a double-acting pump that can be easily installed and repaired by a person having only little mechanical skill.

And still another object of my invention is to provide a double-acting well pump in which the cylinders are arranged vertically, one above the other, and equipped with pistons, both of which are connected to the same actuating member, thus producing a compact pump that can be inserted in a well of small diameter. Other objects and desirable features of my invention will be hereinafter pointed out.

Figure 1 of the drawings is a side elevational view, partly in vertical section, of a double acting pump constructed in accordance with my invention.

Figs. 2 and 3 are vertical sectional views, taken on the lines 2-2 and 3-3, respectively, of Fig. 1.

Figs. 4 and 5 are horizontal sectional views, taken on the lines 4-4 and 5-5, respectively, of Fig. 1; and

Figs. 6 and 7 are vertical sectional views, taken on the lines 6-6 and 7-7, respectively, of Fig. 1.

Referring to the drawings which illustrate the preferred form of my invention, α designates a well and A designates a water discharge pipe that projects downwardly into said well, said discharge pipe being supported by a plate 1 arranged at the mouth of the well, as shown in Fig. 1. My improved pump consists of two opposed cylinders 2 and 3 arranged vertically and submerged in the water in the well, pistons 2^a and 3^a reciprocatingly mounted in said cyl-

inders and a substantially C-shaped actuating member B, to which both of said pistons are connected. The cylinders 2 and 3 are arranged in vertical alinement, one above the other, and the pistons of said cylinders are connected to the short arms or spaced portions 4 of the actuating member B, the part 4^a of said member that connects the arms or portions 4 together being arranged at one side of the cylinders, as shown clearly in Fig. 1. The actuating member B is reciprocated longitudinally of the cylinders by means of a pump rod or link 5 connected at its lower end to the upper end of the member B and having its upper end pivotally connected to a hand lever 6 fulcrumed on a standard 7 mounted on the upper end of the water discharge pipe A. Said discharge pipe is provided with a laterally-projecting branch 7^a that leads to a discharge spout. The inner ends of the cylinders 2 and 3 are formed by two castings 8 and 8^a, respectively, that are secured together in any suitable manner, as, for example, by means of bolts 9, shown in Figs. 3 and 4, that pass through laterally-projecting ears 10 on said castings, and the casting 8 is provided with an internally screw-threaded portion 11 into which the lower end of the water discharge pipe A is screwed. The casting 8^a to which the bottom cylinder 3 is connected is provided with two chambers 12 and 13 that are separated from each other by means of a vertical partition 14, the top walls of both of said chambers being formed by a horizontally disposed partition plate 15 that is arranged between said castings 8 and 8^a. The partition plate 15 is provided with two ports 12^a and 13^a, shown in Fig. 3, that establish communication between the chambers 12 and 13, respectively, and a valve chamber 16 is formed in the portion 11 of the casting 8 to which the discharge pipe A is connected, said ports being controlled by a double flap valve that can be formed conveniently from a piece of rubber, leather or other suitable material 17 that is connected intermediate its ends by screws 18 or other suitable fastening devices to the partition plate 15 and provided with weights 12^b and 13^b that normally hold the two valve portions of the member 17 seated. The partition plate 15 is provided with an opening 12^c, shown in Figs. 2 and 4, that establishes communication be-

- tween the cylinder 2 and the chamber 12 in the casting 8^a, and the bottom wall of the chamber 13 in said casting 8^a is provided with a hole 13^c that establishes communication between the chamber 13 and the cylinder 3. Each of the pistons 2^a and 3^a is provided with a flexible valve 19 that controls inlet ports 20 in the piston, said valves 19 being so arranged that the valve on the piston 2^a will open when said piston moves upwardly, and thus admit water to the cylinder 2, and the valve on the piston 3^a will open and admit water to the cylinder 3 when said piston 3^a moves downwardly.
- 15 When the free end of the operating lever 6 is depressed the pistons in both cylinders will move upwardly, thus causing the water in the cylinder 3 to be forced into the chamber 13, and thence through the port 13^a to the top wall of said chamber into the discharge pipe A, the valve 19 on the piston 2^a being then open so that water can enter the cylinder 2. When the free end of the operating lever 6 is raised the pistons in both cylinders will move downwardly, and thus cause the water in the cylinder 2 to be forced through the opening 12^c in the partition plate into the chamber 12, and thence through the port 12^a in the top wall of said chamber into the discharge pipe A, the valve 19 on the piston 3^a being then open so that water can enter the cylinder 3. It will thus be seen that on each upstroke and on each downstroke of the operating lever of the pump a charge of water will be forced upwardly through the discharge pipe A, thereby causing the water to flow from said pipe in practically a continuous stream, the double acting flap valve which controls the discharge of water from the two chambers 12 and 13 being so constructed that the portion of same to which the weight 12^b is connected will be seated when the water is being forced out of the cylinder 3, and the portion to which the weight 13^b is connected will be seated when the water is being forced out of the cylinder 2.
- The pump rod or link 5 that connects the piston actuating member B to the operating lever 6 is preferably formed from a piece of pipe whose lower end is screwed into a casting 21 provided with a semi-spherical-shaped portion 22 that fits in a socket 23 formed in an ear 24 on the upper end of the member B, said casting 21 being clamped to said ear by means of a bolt 25 or other suitable connecting device. By connecting said parts together in this manner it is possible to set the piston actuating member B in such a position, during the operation of installing the pump, that it will reciprocate in a straight line, even though the pump rod is arranged at a slight angle to a truly perpendicular line. The upper end of the pump rod 5 can be connected to the operating lever

in various ways without departing from the spirit of my invention, but I prefer to connect said elements together by a two-part clevis 26 having coöperating semi-circular-shaped portions that embrace the upper end of the pump rod and which are secured to same by means of a bolt 27, or other suitable connecting device, that passes transversely through said portions and pump rod, as shown in Fig. 7. Each part of the clevis is provided with a perforated ear 28 that receives a transversely-disposed pin 29 in the end of the operating lever 6, said pin being formed integral with the lever 6 or permanently connected to same in any desired manner. The standard 7 on which the operating lever is mounted is formed in substantially the same manner as the clevis 26, above referred to, and comprises two parts secured together and to the upper portion of discharge pipe A by bolts 30 or other suitable fastening devices, each part of said standard being provided at its upper end with a hole for receiving an integral fulcrum pin 31 on the lever 6. A well pump of the construction above described can be easily installed and repaired by a person possessed of only little mechanical skill, owing to the fact that the cylinders of the pump are held in operative position in the well by means of the discharge pipe A, and the piston actuating device B is connected by means of an ordinary pipe and a split clevis to the operating lever 6 of the pump, said clevis and the standard which carries the operating lever being so constructed that they can be combined with the parts with which they co-operate by simply tightening the nuts on a few bolts. My improved pump can be manufactured at a low cost; it is of such simple design that it is not apt to get out of order when in use, and another desirable feature of same is that it is compact and can be arranged in a well of small diameter, this of course being due to the fact that the cylinders are arranged in vertical alinement with each other and the pistons of said cylinder are both connected to a relatively narrow or thin actuating device that reciprocates in a vertical path between the cylinders and the side wall of the well.

Having thus described my invention, what I claim, and desire to secure by Letters Patent, is:

1. A double acting well pump, comprising two cylinders arranged in vertical alinement with each other, a structure arranged between said cylinders and composed of two members each of which is attached to one of the cylinders, a partition plate interposed between said members and clamped between same, two separated chambers in one of said members, a discharge space in the other member, ports in said partition plate that establish communication between said chambers.

bers and said discharge space, a double flap valve connected intermediate its ends to said partition plate for controlling said ports, and means for establishing communication 5 between each of said cylinders and one of said chambers.

2. A double acting well pump, comprising two cylinders arranged in vertical alinement with each other, a casting connected 10 to the upper end of the bottom cylinder and provided with two chambers that are separated from each other by a vertical partition, a port in said casting that establishes communication between the bottom cylinder

and one of said chambers, a second casting 15 connected to the lower end of the top cylinder and provided with a discharge space, a partition plate arranged between said castings and provided with a hole that establishes communication between the top cylinder and the other chamber in the bottom casting, two openings in said partition plate that serve as discharge ports for said chambers, and a double flap valve connected to the top side of said partition plate at a point 20 intermediate said ports. 25

THEODORE PETERS.
